CLAIM

The ornamental design for a bottle, as shown and described.

DESCRIPTION

FIG. 1 is a front perspective view of a bottle, embodying our new design according to a first embodiment;
FIG. 2 is a back perspective view thereof;

FIG. 3 is a front view thereof;
FIG. 4 is a back view thereof;
FIG. 5 is a first side view thereof;
FIG. 6 is a second side thereof;
FIG. 7 is a top view thereof; and
FIG. 8 is a bottom view thereof;
FIG. 9 is a front perspective view of a bottle, embodying our new design according to a second embodiment;
FIG. 10 is a back perspective view thereof;
FIG. 11 is a front view thereof;
FIG. 12 is a back view thereof;
FIG. 13 is a first side view thereof;
FIG. 14 is a second side thereof;
FIG. 15 is a top view thereof; and
FIG. 16 is a bottom view thereof.

FIG. 17 is a perspective view of a bottle, embodying our new design according to a third embodiment;

FIG. 18 is a front view thereof;
FIG. 19 is a back view thereof;
FIG. 20 is a first side view thereof;
FIG. 21 is a second side view thereof;
FIG. 22 is a top view thereof;
FIG. 23 is a bottom view thereof; and
FIG. 24 is a perspective view of a bottle, embodying our new design according to a fourth embodiment;
FIG. 25 is a front view thereof;
FIG. 26 is a back view thereof;
FIG. 27 is a first side view thereof;
FIG. 28 is a second side view thereof;
FIG. 29 is a top view thereof; and,
FIG. 30 is a bottom view thereof.

(Continued)

The bottle disclosed may be made from or include any suitable material and all or any portions thereof can be transparent, translucent, or opaque.

The broken lines shown in the drawings depict portions of the bottle that form no part of the claimed design.
